CLAIM

The ornamental design for the energy storage power supply as shown and described.

DESCRIPTION

1. Energy storage power supply

1.1 : Perspective

1.2 : Front

1.3 : Back

1.4 : Left

1.5 : Right

1.6 : Top

1.7 : Bottom

1.8 : Perspective

FIG. 1.1 to FIG. 1.8 show an energy storage power supply according to the present design; the broken lines shown in the drawings illustrate portions of the energy storage power supply that form no part of the claimed design.
